MOP ASSEMBLY

Sidney L. Smith, Pittsburgh, Pa.

Application August 5, 1938, Serial No. 223,367

1 Claim. (Cl. 15—119)

My invention relates to improvements in mops and has as one of the principle objects thereof the provision of a mop assembly equipped with means whereby water or other liquid may be readily squeezed or exuded from the washing or cleaning element thereof.

Another object of my invention is to provide a mop assembly which is simple in construction, durable in use, efficient in operation and economical in manufacture.

An important object of my invention is to provide a device of the above described character equipped with means for coaction with a pail or other liquid container whereby upon squeezing of the cleaning element the water or the liquid exuded therefrom will be discharged into said pail.

Other objects and advantages will be apparent from the following description, appended claim 20 and annexed drawing.

Referring to the drawing wherein like reference characters designate like parts throughout the several views:

Figure 1 is a perspective view of my invention. Figure 2 is a view similar to Figure 1 illustrating the cleaning or washing element in squeezed or compressed condition.

Figure 3 is a perspective view of my invention with the cleaning or washing element removed therefrom.

Figure 4 is a perspective view of a pail illustrating one part of my invention attached thereto for coaction with one of the frame elements for effecting squeezing of the cleaning element in a manner that the water or other liquids exuded therefrom will be discharged into the pail.

Figure 5 is a detail perspective view of a modified form of one of the frame members.

In practicing my invention, in the preferred embodiment illustrated in Figures 1 to 4 inclusive, I provide a mop assembly comprising a frame 5 on which is operatively mounted a washing or cleaning element 6 and a frame actuator 7 adapted to be detachably secured to a pail or the like for effecting squeezing or compressing of the cleaning element as hereinafter more fully described.

The frame 5 is provided with a length of a substantially rigid wire or the like bent to form a substantially rectangular shaped carrier 10 for the element 6. The free ends of said wire are welded together as at 10a whereby said frame 5 is arranged with side front and rear integrally fashioned sections 11, 12 and 13 respectively.

The outer ends of the sections 12, adjacent the

jointure with the sections 11, are formed with loops 14 providing abutments for the front end of the element 6.

Pivottally mounted on the front section 12, adjacent and inwardly of the loops 14 thereof, are a pair of spaced looped ends 15 of the lower right-angledly disposed portion of a pair of upwardly extending arms 16, the same being constructed of substantially rigid wire or the like. The upper ends of said arms have secured thereover the lower end of a handle 17. The arms 16 are of a relatively short length relative to the sections 11 and are formed intermediate their length with a pair of loops constituting spaced bearings 18 through which is journaled the upper right-angledly disposed end 19 of a pair of integrally fashioned arms 20, the lower ends of which are laterally disposed and formed with loops 21 slidably connected about the sections 11.

The washing or cleaning element 6 comprises a length of suitable material which is folded between the longitudinal ends thereof to form a plurality of convolutions 22. The convolutions are formed with registering apertures provided with eyelets 23 through which extend the sections 11 of the carrier 10 as clearly illustrated in Figures 1 and 2 of the drawing.

When the cleaning element 6 is thus mounted on the carrier 10, the front and rear convolutions thereof are connected to the front section 12 and the lower ends of the arms 20 respectively and thereby position the other convolution between said sections 12 and 13. Obviously, when the frame 5 is in extended or cleaning position, as illustrated in Figures 1 and 3, the element 6 is in expanded condition as illustrated in Figure 1. In this position, the element 6 is adapted to absorb and retain an appreciable quantity of water or other liquid when dipped into the pail 8 containing the same.

The frame actuator 7 comprises a length of semi-resilient wire or the like bent to form pairs of spaced vertically extending inner and outer arms 24 and 25 respectively. The lower ends of the outer arms 25 terminate in an integrally formed angular disposed foot piece 26 adjacent and outwardly of the bottom of the pail 8. The lower ends of the inner arms 24 are bent upwardly and provide a pair of upwardly extending portions 27, the upper ends of which are fashioned with an inwardly and downwardly extending integral hook 28 for engagement with the rear section 13 of the carrier 9 as hereinafter set forth.

When the cleaning element 6 has been dipped

into the water or the like contained in the pail 8, the rear section 13 of the carrier 10 is hooked under the hook 28 and the handle 17 operated upwardly to cause the loops 21 of the arm 20 to slide towards the front section 12 of the carrier and thus compress the element 6 therebetween. When the element 6 is thus compressed, excess water or the like contained therein will be discharged into the pail 8, it being understood that the element 6 and frame is disposed over the top of the pail during the exuding or squeezing operation and thereby preclude waste of the water on to the area without the pail.

From the foregoing, it will be apparent, that I have provided a simple and efficient means forming a part of a mop assembly whereby the mop or cleaning element may be readily relieved of excess water, the actuator 7 coacting with the carrier to effect discharge of the water into the pail. The foot piece 26 of the actuator 7 enables the operator, by means of a foot secured on the foot piece 26, to maintain the pail in a fixed position and precluding overturning of the latter.

In the modified form illustrated in Figure 5, the carrier 30 therein is fashioned with a pair of side sections 31, the rear ends of which termi-

nate in right-angular and inwardly disposed loops 32 forming abutments for the eyelets in the rear convolution of the element 6. When it is desired to compress the element 6, one of said loops may be engaged under the hook 28 to effect squeezing of said element upon upward movement of the handle.

It is to be distinctly understood that various changes and modifications may be resorted to in the construction and arrangement of parts without departing from the spirit of the invention or scope of the appended claim.

I claim:

A device of the character described, comprising, a frame having a carrier equipped with side front and rear sections, a handle pivotally mounted on said front section, a pair of arms slidably connected to said side sections and normally positioned adjacent said rear section, and a compressible cleaning element slidably mounted on said side sections between said front section and said arms, said arms pivoted to said handle whereby movement of said handle serves to actuate said arms toward said front section and compress said element therebetween.

SIDNEY L. SMITH.
